US00D664942S

(12) **United States Design Patent**
Boucquey et al.

(10) **Patent No.:** **US D664,942 S**
(45) **Date of Patent:** **** Aug. 7, 2012**

(54) **COMMUNICATION DEVICE**

(75) Inventors: **Thomas D. Boucquey**, Chicago, IL (US); **Dave H. Karl**, Fort Lauderdale, FL (US); **Claudio Santiago Ribeiro**, Evanston, IL (US)

(73) Assignee: **Motorola Mobility LLC**, Libertyville, IL (US)

(**) Term: **14 Years**

(21) Appl. No.: **29/402,165**

(22) Filed: **Sep. 21, 2011**

(51) **LOC (9) Cl.** **14-03**

(52) **U.S. Cl.** ..... **D14/138 AA**

(58) **Field of Classification Search** ..... D14/138 AA, D14/138 R, 138 C, 496, 346, 203.1, 203.4, D14/203.7, 147, 148, 218, 426; D21/517; 455/575.1, 556.2; 379/433.01, 433.04; D13/168

(57) **CLAIM**

The ornamental design for a communication device, as shown and described.

DESCRIPTION

FIG. 1 is a front perspective view of an ornamental design for a communication device;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines shown throughout the views that are immediately adjacent to the shaded areas, and define unshaded regions, represent the bounds of the claimed design, while all other broken lines are directed to environment and are for illustrative purposes only; the broken lines form no part of the claimed design.
